UNITED STATES PATENT OFFICE.

RALPH ADAMS, OF PORTLAND, OREGON.

SCREEN-CLEANING DEVICE FOR SPARK ARRESTERS.

Application filed July 27, 1922. Serial No. 577,898.

To all whom it may concern:

Be it known that I, RALPH ADAMS, a citizen of the United States, and a resident of Portland, county of Multnomah, and State 5 of Oregon, have invented a certain new and useful Improvement in Screen-Cleaning Devices for Spark Arresters, of which the following is a specification.

One of the main objects of my invention is 10 to provide screen cleaning means for spark arresters and the like which are positioned in otherwise inaccessible places.

A further object is to lessen the fire hazard 15 in logging engines due to defective or inadequate spark arresters.

A further object is to provide means for 20 improving the draft of logging engines inasmuch as my invention can remove clogged surfaces from the spark arrester screen which will otherwise decrease the heating capacity of the logging engine boilers.

Spark arresters as now constructed are placed in position on smoke stacks and are left at the mercy of the elements and are 25 replaced only when entirely inoperative. This condition is especially harmful in logging operations, especially in the western woods inasmuch as the fuel used is almost entirely wood and defective draft cuts down 30 the heating efficiency of the engine. Engineers, to overcome this fault open the throttle and shake down the fuel in the boilers causing great quantities of sparks to be forced thru the screen. This temporarily opens the 35 clogged surfaces but increases the fire hazard. The spark arresters are placed on the engines primarily to eliminate the danger of forest fires caused from sparks falling on the slashings immediately surrounding the engine. 40 This action of the engineer which is necessary to keep up the pressure in the boilers defeats the purpose for which the arresters were intended and are thus a source of constant danger. It is impractical for the 45 firemen to climb upon the roof of a logging engine and clean the spark arrester as they are usually hot and in almost inaccessible places. The foregoing facts are equally adaptable to locomotives and stationary 50 heating plants.

By my invention the operator can clean the screens readily by merely opening a valve and causing the steam or air to pass thru the screens rapidly and clean the clogged 55 meshes. If steam is used the inherent moisture will also dampen and cool the arrester

itself. Thus, during the shaking down operation, the operator could open this valve and dampen the lighted sparks which would force their way thru the screen and render 60 them harmless.

I attain these objects in the combination with a spark arrester having a perforated section, of a pipe arranged relatively to said perforated section and relatively movable 65 over the latter, said pipe communicating with a source of fluid under pressure, spraying orifices in said pipe disposed to emit jets against said perforated section, another orifice in said pipe disposed to emit a jet at 70 an angle to said perforated section thereby to cause the reaction due to the latter jet to give relative movement to said pipe, and means actuated by centrifugal force for restraining the rate of said movement. 75

My screen cleaner will successfully remove any oil deposits which are contained in the smoke and the surface will always be bright and free from corroding incrustations.

These and other objects are illustrated in 80 the accompanying drawings, in which:

Fig. 1 is a side elevation of my screen cleaner with parts broken away to show features of construction;

Fig. 2 is a top or plan view of Fig. 1 and 85 indicates the direction of rotation of the cleaning pipes;

Fig. 3 is a diagrammatic representation of the section of my cleaning device taken on the line 3—3 of Fig. 1 showing the cleaning 90 jet as normal to the screen and the propelling jet at an angle so as to rotate the vapor carrying pipes around the spark arrester;

Fig. 4 is a detail view taken on the line 4 95 of Fig. 1 and shows the position of the cleaning ports;

Fig. 5 is a similar detail view taken on the line 5 of Fig. 1 and shows the cleaning port as spaced between the similar ports in Fig. 4 and the propelling port as slightly on 100 an angle and near the top of the device;

Fig. 6 is a fragmentary section taken on the line 6—6 of Fig. 2 and shows details of construction of the rotary head;

Figs. 7 and 8 are detail views showing the 105 construction of the brackets which hold the cleaning pipes;

Fig. 9 is a plan view of a different type of spark arrester embodying my invention;

Fig. 10 is a sectional view taken on the 110 line 10—10 of Fig. 9 and shows diagrammatically the operation of the cleaning de-

vice removing the incrustations on the interior screen;

Fig. 11 is a plan view of still another type of spark arrester;

Fig. 12 is a sectional view taken on the line 12—12 of Fig. 11 and also shows in diagram the action of the cleaning pipes;

Fig. 13, taken on the line 13—13 of Fig. 12 shows details of construction of the cleaning pipes; and

Fig. 14 is a fragmentary section taken on the line 14 of Fig. 12 and shows in diagram the action of the cleaning pipes.

My device is positioned on any standard common form of spark arrester as *a*. A hollow standard or pipe *b* is connected with some convenient source of supply and is connected to the perpendicular intake pipe *c* which passes thru the top *d* of the spark arrester *a*. On the pipe *c* is mounted a rotary head *e*, on the top *d*, and held in place by a nut *f*. Between the top *d* and the nut *f* the rotary head is allowed rotation. Horizontal pipes *g* and *h* are connected with the rotary head *e* and the fluid passes thru them and thence to the cleaning pipes *i* and *j* respectively. Ports *k* and *l* are positioned in the cleaning pipe *j* and the fluid passes thru them and forces the incrustations on the screen inwardly and away from the screen. The port *m* positioned in the pipe *i* performs a similar function. Port *n* in the pipe *i* is positioned at an angle to the screen and the fluid rushing thru it and striking the screen causes the cleaning pipes to rotate, the sides of the port being regulated by the speed desired in the cleaning pipes. The cleaning pipe is positioned and plugged by the bracket *o* fastened to the supporting band *p*. The pipe *j* is positioned in and plugged by the bracket *o'* which is also connected to the band *p*. The band *p* is relatively flexible and the cleaning pipes hang pendent from their connections with the pipes *g* and *h* respectively. When the cleaning device is rotated, the cleaning pipes *i* and *j* tend to swing outwardly and this action forces the band *p* against the sides of spark arrester and the friction limits the speed of rotation of the device. The rotary head is made with an incision *q* which meshes with the port *r*, in the perpendicular pipe *c*. The perpendicular pipe *c* is made with a shoulder *s* which presents a bearing on which the rotary head can revolve. I have provided a hardened wearing plate *t* positioned on this bearing so as to take the wear of this rotary head. In Figs. 9 and 10, embodying the arrester *a'*, a similar device is provided. Fluid enters thru the pipe *b'*, thence thru the perpendicular pipe *c'*, thence to the rotary head *e*. The cleaning pipes *i'* and *j'* perform similar functions to *i* and *j* in the previously described pipe. They are plugged and held

at their upper end by transverse members *u* and *u'*.

In Figs. 11 and 12 embodying the arrester *a'*, fluid enters thru a pipe *b'*, thence thru a perpendicular pipe *c'*, thence thru the rotary head *e* and thence to the cleaning pipe *i''* and *j''* and are plugged by the caps *v* and *v'*. The fluid passes out thru the cleaning ports *k''*, *l''*, and *m''* and thru the propelling ports *n''*.

I claim:

1. The combination with a spark arrester, of means for cleaning the perforated section of the latter comprising, a sprayer connected with a source of fluid under pressure, movable over said perforated section, the sprayer being adapted to emit jets of spray against the latter, and an auxiliary jet for moving the sprayer over the perforated section.

2. The combination with a spark arrester having a perforated section, of means for cleaning the perforated section comprising, a sprayer connected with a source of fluid under pressure rotatably mounted on the spark arrester, adapted to revolve relatively to said perforated section, and to emit jets against the latter, said sprayer also adapted to emit an auxiliary jet at an angle against said spark arrester thereby to cause relative revolution of said sprayer.

3. The combination with a spark arrester having a perforated section, of means for cleaning the perforated section comprising, a sprayer connected with a source of fluid under pressure rotatably mounted on the spark arrester, adapted to revolve relatively to said perforated section and to emit jets against the latter, said sprayer also adapted to emit an auxiliary jet at an angle against said spark arrester thereby to cause the relative revolution of said sprayer, and means actuated by centrifugal force for restraining the speed of said relative revolution.

4. The combination with a spark arrester, having a perforated section, of spraying means connected with a source of fluid under pressure and adapted to revolve over said perforated section, arms, included in said spraying means supported at one end and adapted to be affected by centrifugal force, and a brake band, encompassing said spark arrester carried by the free ends of said arms.

5. The combination with a spark arrester having a perforated section, of a pipe arranged relatively to said perforated section and relatively movable over the latter, said pipe communicating with a source of fluid under pressure, spraying orifices in said pipe disposed to emit jets against said perforated section, another orifice in said pipe disposed to emit a jet at an angle to said perforated section, thereby to cause the reaction

due to the latter jet to give relative movement to said pipe.

6. The combination with a spark arrester having a perforated section, of a pipe arranged relatively to said perforated section and relatively movable over the latter, said pipe communicating with a source of fluid under pressure, spraying orifices in said pipe disposed to emit jets against said perforated section, another orifice in said pipe disposed to emit a jet at an angle to said perforated section thereby to cause the reaction due to the latter jet to give relative movement to said pipe, and means actuated by centrifugal force for restraining the rate of said movement.

7. The combination with a spark arrester having a perforated section of spraying means comprising a hollow standard, axial with the spark arrester, connected with a source of fluid under pressure, a rotary head mounted on said standard, laterally extending hollow arms carried by said rotary head, the latter having a port connecting the hollow arms with the hollow standard, other arms parallel with the standard fastened at one end to the free ends of said lateral arms, one of said parallel arms provided with spraying orifices disposed to emit a jet against the perforated section of the spark arrester and provided also with another orifice disposed to emit a jet at an angle to said spark arrester, thereby to cause the reaction due to the latter jet to revolve said rotary head.

8. The combination with a spark arrester having a perforated section of spraying means comprising, a hollow standard, axial with the spark arrester, connected with a source of fluid under pressure, a rotary head mounted on said standard, laterally extend-

ing hollow arms carried by said rotary head, the latter having a port connecting the hollow arms with the hollow standard, other arms parallel with the standard fastened at one end to the free ends of said lateral arms, one of said parallel arms provided with spraying orifices disposed to emit a jet against the perforated section of the spark arrester, and provided also with another orifice disposed to emit a jet at an angle to said spark arrester, thereby to cause the reaction due to the latter jet to revolve said rotary head, a break band encompassing said spark arrester carried by the free ends of said parallel arms.

9. The combination with a spark arrester having a perforated section of spraying means comprising, a hollow standard, axial with the spark arrester, connected with a source of fluid under pressure, the upper end of said standard being shouldered, a rotary head mounted on said standard, and bearing on the head of the spark arrester, a washer on the upper end of said head, a nut threaded on said shouldered end of the standard, laterally extending hollow arms carried by said rotary head, the latter having a port connecting the hollow arms with the hollow standard, other arms parallel with the standard fastened at one end to the free ends of said lateral arms, one of said parallel arms provided with spraying orifices disposed to emit a jet against the perforated section of the spark arrester, and provided also with another orifice disposed to emit a jet at an angle to said spark arrester, thereby to cause the reaction due to the latter jet to revolve said rotary head, a break band encompassing said spark arrester carried by the free ends of said parallel arms.

RALPH ADAMS.
